NOISE SUPPRESSION CIRCUIT

Lav Kamenarovic, Milan, Italy, assignor to Radio Corporation of America, a corporation of Delaware

Application October 15, 1938, Serial No. 235,151
In Italy October 29, 1937

3 Claims. (Cl. 250--20)

Radio receiver apparatus comprising means adapted to the automatic control of the volume or sensitivity and their operation involve the problem of suppressing the reproduction of noises in the intervals between the stations or the carrier waves by what is known in the art as silent tuning.

As a matter of fact, the automatic volume control means tend to stabilize the level with which the signals act upon the receiver and as a result modify the sensitiveness or responsiveness of the receiver set in inverse proportion to the intensity of the incoming signals. Therefore, during the intervals between the various stations or carriers the automatic volume control acts in the sense of raising the sensitivity to the maximum value and as a result raises unduly and excessively also the noise level so that the receiver set works very noisily while "fishing" for or tuning in the various transmitter stations.

To the end of avoiding these difficulties silent tuning means have been disclosed in the prior art which are adapted to render inactive or inoperative the receiver set whenever the incoming signals fall below a predetermined level, and this is designed to eliminate to a large part the disturbing actions or noises the level of which as a general rule is fairly low, and to insure the tuning of transmitter stations in the presence of normal volume and under fairly noiseless conditions. However, the ways and means disclosed in the art to this end have fallen short of fulfilling requirements; in fact, when a station which is to be received is subject to fluctuations, for instance, as a result of fading, about the level at which the silent tuning means is caused to become operative, reception will be periodically interrupted and restored at full volume, while if the signal is maintained for a certain length of time at the stated level, the reception or reproduction turns out to be seriously distorted on the ground that the circuit is in a critical operating state.

The before-mentioned inconvenience can not be eliminated simply by fixing at a lower point the level where the silencing means is caused to enter into operation nor can this be achieved by making the said level regulable or variable, because in the first case it is not possible satisfactorily to eliminate the noise while attempting to tune in a station, whereas in the second case, if regulation is fixed at a level high enough to insure silence or freedom from noise in the intervals between carrier waves, there is a risk of

mutilating signals subject to fading even when not very strong.

The present invention has as its object a silent tuning or a noise suppressing means which is adapted to obviate the above-mentioned difficulties. In fact, by the aid of the same it is possible to make conditions so that when the silent tuning means is rendered inactive at a given signal level, the same is reactivated or restored to operating condition only when the signal falls to a level far below the level where inactivation occurs. Hence, once reception of a given station or signal has been established, such reception is maintained, subject to the action of the automatic volume control means, even when such station signal experiences an appreciable weakening or fading. On the contrary, when tuning the receiver set to another station, the very strong drop in input which at all events happens in the interval between carrier waves insures operation of the silencing or noise suppressing means.

The appended drawing Fig. 1 schematically represents an arrangement predicated upon the invention as applied to a receiver set of which are shown merely such elements as are strictly indispensable in connection with the present invention. Fig. 2 is a schematic view of a modification of part of the arrangement. Figs. 3 and 4 are graphs adapted to explain the behavior and operation of the arrangement here disclosed.

Referring to the key diagram Fig. 1, A is an I. F. amplifier upon the grid of which are brought to act the signals coming from the frequency converter circuit CF in the case of a superheterodyne receiver, which, in turn, is excited from the antenna circuit. The said valve A could also form a part of the last RF stage where a tuned RF type of receiver is concerned, the plate of the said valve or tube being connected with the tuned circuit 1, and across a capacitor c₃ with the oscillating circuit 2.

The oscillatory circuit 1 inductively excites an oscillatory circuit 3. To the terminals of the capacity of the latter are connected the plate and across capacitor c₁ the cathode of a diode D₁ while connected with oscillatory circuit 2 in a similar manner are the anode and the cathode of a diode D₂, with a capacitor c₂ being interposed in the cathode lead.

Connected with the terminal of the oscillatory circuit 3 united with c₁, by way of conductor 4, is the anode of a silencing valve S which is also connected with the circuit of the grid of valve A across the resistances 6 and 6', which, con-

jointly with capacitor c_6 constitutes a filter adapted to level or smooth the biasing potential, while conductor 4 is connected with a terminal of a resistance R_2 whose opposite terminal is united with the cathode of diode D_1 . Fitted on resistance R_2 is an adjustable tap or slide 7 to which is connected a conductor 8 which forms the terminal of and is brought to the AF circuit (BF) of the receiver.

The oscillatory circuit 2 is connected with ground through 9 and the resistance R_1 . The terminal of the said resistance R_1 which is united with circuit 2 is also connected through 18 with the grid of the silencing tube S across the resistance R_3 ; the opposite terminals of the latter are grounded by way of capacitors c_4 and c_5 , respectively.

The cathodes of valve A and of diode D_1 are connected by means of leads 10 and 11 with a movable slide or tap 13 on a resistance 14 having one terminal connected with a positive source of supply, while the opposite terminal is grounded. The cathode of diode D_2 is similarly connected by way of conductor 15 and the slide 16 with a resistance 17 connected between a positive source of supply and the ground.

Supposing a signal is received at a level adapted for normal reception subject to the action of the automatic volume control means, if taps 13 and 16 are placed on the ground-end terminals of the respective resistances 14 and 17 , the silencing means is prevented from becoming operative. In fact, detection insured by diode D_1 gives rise to a negative potential across the terminals of resistance R_2 , and the anode of silencing valve S is rendered negative with the result that the said valve precludes the flow of current to the conductor 4 . The alternating component of the potential obtaining across the terminals of resistance R_2 acts through 7 and 8 upon the AF circuit BF of the receiver apparatus, while the D. C. component is brought to act through 6 and 5 upon the grid of valve A with a view to producing automatic volume control action, as well known in the art, by virtue of a modification of the biasing of the grid of tube A as a function of the strength of the incoming and detected signal.

Rectification in diode D_2 of the said incoming signal impresses through 9 and 18 a negative bias upon the grid of valve S thereby assisting in maintaining the same inoperative.

Supposing that taps or slides 13 and 16 are shifted away from the ground-end terminals of resistance 14 and 17 , there will act on the said taps and their respective conductors 10 , 11 and 15 positive potentials hereinafter to be called V_1 and V_2 . The positive potential V_1 is applied to the cathode of tube A and to the cathode of diode D_1 and across R_2 to the anode of valve S whose internal drop, in the absence of a signal, may be considered negligible in comparison with the resistance R_2 because under these conditions its grid is connected with ground so that the valve presents a low inner resistance for direct current. Consequently, the voltage V_1 applied to the cathode of diode D_1 results in a D. C. which is made through ground across R_2 and S . The D. C. potential corresponding to the fall caused by this current across the terminals of the resistance R_2 is impressed through 6 and 5 upon the grid of amplifier valve A and furnishes the initial biasing action which reduces the amplification or gain thereof. The same drop, on the other hand, acts as a positive bias upon diode D_1 and thus maintains the cathode of diode D_1 more positive than

the anode and prevents the detection of alternating currents of the signal fed from valve A to diode D_1 by way of circuits 1 and 3 having an intensity or strength less than that corresponding to the said biasing action.

Similarly, the biasing of diode D_2 insured by potential V_2 prevents detector action in the said diode of signal currents fed thereto from tube A across c_3 and 2 , c_2 as long as such signal currents do not surpass the value corresponding to biasing voltage V_2 .

The receiver therefor is silent inasmuch as detector action in D_1 is precluded, and the responsiveness thereof is diminished by virtue of the action of potential V_1 upon the grid of tube A . The receiver stays silent as a result of the cut-off of diode D_1 even if the intensity of the signal grows to a certain extent.

When the signal reaches a value (s_1) so as to result in 2 in an alternating tension V_s sufficiently high to overcome the positive biasing action produced by potential V_2 upon diode D_2 , detection of the signal will be brought about by the said diode and there arises a negative potential across the terminals of R_2 and therefore upon the grid of tube S .

In the presence of conditions as described, the inner resistance of valve S for D. C. increases; and as a result there occurs a decrease in the current which flows through resistance R_2 as a result of potential V_1 and the drop of potential across the terminals of R_2 . As a result the biasing potential acting upon the grid of tube A due to V_1 decreases, thereby resulting in a growth in gain of this valve, which, in turn, is attended with a growth in signal strength acting upon diode D_2 . This increase in signal strength, in turn, raises still further the negative bias acting upon the grid of S and the inner resistance of this valve with a further reduction of the current due to V_1 flowing in resistance R_2 and the bias action upon the grid of tube A so that the gain of this valve thereafter is caused to grow.

The inner resistance of the silencing valve S therefore tends instantaneously to assume the maximum value permitted by and corresponding to the circuit constants and the intensity of the incoming signal, thereby resulting in the suppression of the biasing action due to V_1 upon diode D_1 and upon the grid of tube A , with the consequence that the diode D_1 insures normal detector action to excite the AF circuit, whereas the D. C. component resulting from the detector action in diode D_1 produces the normal AVC action upon valve A , in the presence of which, on the contrary, silencing valve S is no longer operative. This operation which is the same as that already described in the absence of voltage V_1 subsists for the entire length of time for which the incoming signals inhere sufficient intensity to result in D_2 a potential V_s capable of overcoming the action of constant potential V_2 , taking into consideration the gain established in valve A by action of the same diode D_2 with exclusion of the initial bias potential across the terminals of R_2 .

Taking into consideration that the action of diode D_2 in the sense of cutting off the silencing valve S is initiated when the signal potential V_s acting upon diode D_2 is capable of surmounting potential V_2 while valve A operates at the low gain corresponding to the total drop produced by V_1 across resistance R_2 , it evidently follows that the conditions adapted to activate or render operative the valve S so as to make the receiver set silent are able to be restored again only when

the intensity of the signal falls below a value s_0 which is appreciably lower than s_1 .

Conditions are therefore made so that during intervals between stations or carriers the receiver apparatus will stay perfectly silent so far as disturbing actions are concerned even when these reach an appreciable level, once that normal operation has been established at a level adequate to produce the cut-off of the silencing valve, and this operating state subsists also in the presence of the possible condition where the station signals suffer considerable fading, though there is, on the contrary, a tendency of such fading being compensated by virtue of the automatic volume control. In practice it is possible to make the ratio between the signal voltage (s_1) corresponding to the cut-off of the silencing valve and the potential of the signal (s_0) corresponding to the activation or operation of the said valve equal to 500, it being thus possible to preclude all disturbances and interference during inter-station intervals and permit very appreciable losses of the signal in reception without the receiver apparatus being rendered silent.

Adjusting potentials V_1 and V_2 by setting the slides or taps 13 and 16 conveniently, it is possible to regulate at will and independently of each other the signal levels for which activation or operation of the silencing valve and its inactivation are produced which correspond to the before-mentioned values s and s of the signal.

As a matter of fact, by shifting slide 16 away from the ground-end terminal of resistance 17, the potential V_2 fed to diode D_2 is raised with a resultant raise of the values of the signal potentials (V_{s1} and V_{s0}) in the presence of which the cutoff and the opening or unblocking of the silencing tube takes place. If, on the contrary, slide 13 of resistance 14 is moved in a direction away from the ground-end terminal thereof, potential V_1 is raised, and this means an increase in the initial biasing of the grid of tube A in the sense of lower gain, thereby raising the level of the incoming signal potential (s_1) for which the silencing valve S is cut off without an incidental change in the level of the incoming signal potential (s_0) in the presence of which the said valve is opened or re-activated. Hence, by the combined adjustment of taps or slides 16 and 13 it is possible to change independently of each other the points where the silencing valve is opened and where it is cut off.

Fig. 2 illustrates regulating means adaptable to the circuit organization hereinbefore disclosed by substituting for the assembly Z in Fig. 1 comprising elements 13, 14, 16, 17, the assembly of regulator means Z' shown in Fig. 2, while the rest of the organization shown in Fig. 1 remains unchanged.

In this case, the conductors 11 and 15 which are brought to the cathodes of diodes D_1 and D_2 are connected jointly to a common point of a resistance 19, one terminal of which is grounded, while the other terminal thereof is united with the conductor 10 which is brought to the cathode of tube A. Between the said cathode and the resistance 19 is shunted to ground a variable resistance R_4 .

The potential across resistance R_4 corresponds to the fall produced by the filament current of amplifier tube A. Potentials V_1 and V_2 are here replaced by one potential arising across the terminals of portion R_6 of resistance 19 included between the variable tap 20 and ground, whereas

section R_5 stays permanently included between the filament and the grid of valve A, thereby resulting in a permanent biasing action, which persists also after cut-off of valve S, to regulate the gain of valve A.

By regulating the value of R_4 there results a corresponding change of the potential across the terminals of R_6 and this results in a change both in the point where the valve S is unblocked as well as the point where it is cut off; there is changed at the same time also the potential across the portion designated by R_5 and thus also the effective responsiveness or sensitiveness of the valve A after valve S has been cut off.

Changing, finally, the ratio between sections R_5 and R_6 it is possible to insure a far wider regulation of the range between the points where silencing tube S is opened and where it is cut off.

This regulation means offers the advantage that it is possible to use a double diode tube comprising a joint filament or cathode since the leads 11 and 15 may be combined in a single conductor; that additional sources of supply of potential are dispensable, and that, finally, it is possible to regulate simultaneously the cut-off point of the silencing valve and the gain of tube A and thus the effective sensitiveness of the receiver set in its normal operation after the silencing tube has been cut off.

Fig. 3 is shown to explain more clearly the behavior and operation of circuit organizations of the kind hereinbefore disclosed. Referring to Fig. 3 the abscissae stand for incoming signal voltages (s) while the ordinates stand for the values of the potentials acting upon D_2 and thus the D. C. potential V_2 applied to the cathode of the said diode and the amplitude of the potential V_s of the amplified signal acting between the cathode and the anode of the said diode. Assuming that the receiver is in silent state, plotting the incoming signal from O to the value s_0 (abscissa), the alternating potential V_s acting on V_2 grows linearly and to a limited extent since the diode D_1 is maintained inactive so that the AVC is inoperative, while, on the other hand, upon the grid of tube A there acts the bias corresponding to the fall produced by the current which flows through the resistance R_2 and valve S being still active by virtue of the potential V_1 applied thereon.

When the incoming signal has a value s_1 and the potential impressed upon diode D_2 reaches a value V_{s1} equal to V_2 the operation is such as described, that is, diode D_1 becomes operative and there occurs an increase in gain (as represented by the ratio of the ordinate and abscissa of the straight graph V_s and thus by the tangent of the angle between V_s and the abscissa axis) from the value a_1 to value a_2 as a result of the action as described upon the grid of valve A. Potential V_{s1} acting between the anode and the cathode of diode D_2 , by virtue and as a consequence of variation of amplification or gain, changes instantaneously to value V_{s2} . If, then, the value of the incoming potential s diminishes, the gain preserves its higher value a_2 , the potential V_s upon the diode D_2 is not restored to the value V_{s1} , but decreases in accordance with curve $V_{s2}-V_{s0}$, the trend or shape of the curve being also a function of the automatic volume control. If, by varying along this curve the potential upon D_2 decreasing from the value V_{s2} reaches value V_{s0} equal to V_2 , there is brought about the operation or opening of valve S, and this makes the receiver set silent again.

Setting potential V_2 at another value, say, V'_2 , there results a similar behavior as represented by points $Vs'1$, $Vs'2$ and $Vs'0$.

In other words, potential Vs follows the shape of the curve $O-Vs_1-Vs_2$ as the incoming signal potential grows from O to s_1 , while the same varies according to the curve $Vs_2-Vs_0-Vs_{00}$ and eventually O (if the incoming signal diminishes still further) while the incoming signal potential varies from s_1 to s_0 (and to O).

Fig. 4 illustrates the corresponding trend and shape of the A. F. incoming potential (ordinate: $t(bf)$) plotted against the incoming signal potential (abscissa: s). The A. F. incoming potential is O during the intervals where the incoming signal potential grows from O to s_1 whereas the same varies according to the curve $Ts_1-Ts_2-Ts_0-O$ while there occur variations in decreasing sense of the incoming signal potentials from value s_1 to value s_0 .

What is claimed is:

1. In a radio receiver of the type comprising a signal amplifier followed by a detector having a load impedance across which is developed detected signal voltage, the improvement which comprises a direct current voltage connection from the load impedance to said amplifier for gain control of the latter, an electron discharge device including said load impedance in its space current path and normally developing across the impedance a direct current voltage applied to said detector in detection-suppression sense, a diode rectifier for deriving a direct current voltage from amplified signals, means for applying the derived voltage to said electron discharge device in a sense to prevent development of said suppression voltage, and variable bias means in circuit between the diode anode and cathode for rendering said diode rectifier ineffective in the absence of signals whose amplitude exceed a predetermined magnitude.

2. In a radio receiver of the type comprising a signal amplifier followed by a diode detector having a load impedance across which is developed

detected signal voltage, the improvement which comprises a direct current voltage connection from the load impedance to said amplifier for gain control of the latter, an electron discharge device including said load impedance in its space current path and normally developing across the impedance a direct current voltage applied to said detector in detection-suppression sense, a second diode for deriving a direct current voltage from amplified signals, means for applying the derived voltage to said electron discharge device in a sense to prevent development of said suppression voltage, variable bias means in circuit between the second diode anode and cathode for rendering said second diode ineffective in the absence of signals whose amplitude exceed a predetermined magnitude, and means for rendering the said electron discharge device conductive in the absence of signals of a predetermined amplitude and the electrodes of said two diodes being in a common tube envelope.

3. In combination with the signal amplifier of a radio receiver, a pair of diodes, means for impressing signals upon one diode from said amplifier, a load resistor in circuit with said one diode for developing audio voltage from the rectified signals, an automatic gain control connection from the resistor to said amplifier, means for concurrently adjusting the cathode potentials of each of said amplifier and one diode, means for impressing signals upon the second diode from said amplifier, an impedance in circuit with the second diode for developing a unidirectional voltage from rectified signals, means for separately adjusting the second diode cathode potential, an electron discharge tube including said load resistor in its space current path whereby space current flow through the load resistor develops a unidirectional voltage, said latter voltage being applied to said one diode in rectification-suppression sense, and means for applying the second diode voltage to said electron discharge tube in a sense to reduce its space current flow.

LAV KAMENAROVIC.
